UNITED STATES PATENT OFFICE.

HORACE J. PETERSON, OF MONTPELIER, IDAHO.

GUN.

1,278,737.

Specification of Letters Patent. Patented Sept. 10, 1918.

Application filed February 19, 1918. Serial No. 218,095.

To all whom it may concern:

Be it known that I, HORACE J. PETERSON, a citizen of the United States, residing at Montpelier, in the county of Bear Lake and State of Idaho, have invented certain new and useful Improvements in Guns, of which the following is a specification.

The object of this invention is to provide means whereby rapid-fire guns may be fired without the use of explosives or introducing gases into the barrel or bore of the gun.

The invention also seeks to provide simple means whereby the gun may be aimed in any desired direction, and also to provide operating mechanism which will be simple in construction and operation and prove efficient and inexpensive in use.

The several stated objects are attained in mechanism such as is illustrated in the accompanying drawings, and the invention resides in certain novel features which will be hereinafter fully described and then more particularly pointed out in the claims.

In the annexed drawings, which illustrate one embodiment of my invention, Figure 1 is an elevation of a machine-gun embodying my improvements.

Fig. 2 is an enlarged plan view of a pair of guns and the mounting for the same.

Fig. 3 is a longitudinal section of a gun embodying my invention and showing the same aimed in a downward direction with the parts in the position assumed after discharge.

Fig. 4 is a similar view showing the gun aimed upwardly and the parts in the position assumed immediately prior to a discharge.

Fig. 5 is a detail sectional view of a portion of the gun mount.

In carrying out my invention, I mount the gun upon an automobile indicated at 1, which may be of any well known type as regards its driving mechanism and the forward portion of the frame. The usual body, however, is omitted and, upon the rear portion of the frame, a base or pedestal 2 is rigidly secured. Upon this pedestal is hingedly mounted a base or platform 3 so that it may be tilted vertically and a gun, mounted thereon, thereby aimed upwardly or downwardly. The particular form of the hinge connection between the platform and pedestal is immaterial and is shown conventionally at 4. Co-acting with the hinge connection is a locking mechanism which is

adapted to bear upon the platform in such manner as to hold it in any position in which it may be set. The platform is preferably circular and has an upturned rim 5 at its edge which rim is adapted to overlap the edge of a turn table 6 which is carried by the platform and is supported thereon through the medium of anti-friction devices shown at 7. An arcuate internal rack 8 is secured to and depends from the underside of the platform and this rack is engaged by a pinion 9 mounted upon the frame of the automobile and meshing with the pinion 10 which is carried by a shaft journaled in the pedestal 2, a crank or handle 11 being so disposed that it may be readily grasped by the operator to bring the platform and turn table into the desired inclination. The turn table 6 is constructed with teeth 12 on its edge which mesh with a pinion 13 secured upon the lower portion of an adjusting shaft 14 which is rotatably mounted in the platform 3 and in the upper end of a post or column 15 erected on the platform and enclosing the shaft as clearly shown. An operating hand wheel 16 is secured upon the upper extremity of the shaft and below said extremity a spur wheel 17 is secured upon the shaft. This spur wheel may be engaged by a dog 18 carried by an arm or bracket 19 projecting from the base 15 so that the shaft may be held against rotation and the turn table, consequently, held in any position to which it may be brought.

Upon the turn table, I secure standards 20 which are disposed at opposite sides of the central longitudinal plane of the machine and somewhat in advance of the center of the turn table, as clearly shown in Fig. 2. The standards are rigidly secured to the turn table and, of course, follow all the movements of the same. Upon the upper end of each standard, I secure a carriage or base 21 on which a gun barrel 22 is mounted, the barrel being preferably pivoted to the carriage 21 so that it may move in a vertical plane relative to the mount and greater accuracy of aim be thereby attained. The gun barrel is constructed with a bore 23 of a proper diameter to accommodate bullets or other projectiles to be discharged therefrom and upon the upper side of each gun barrel, I secure a hopper 24 which is intended to be filled with the projectiles prior to the operation of the gun. The rear end of the gun barrel, which is

ordinarily fitted with a loading mechanism or other breech end construction, is, according to my invention, left open, as shown at 26, and in the upper and lower walls of the barrel are slots or notches 27 to accommodate the angular movement of a pitman 28 which passes into the barrel through the rear end thereof and is pivoted to a plunger 29 slidably fitted within the barrel and adapted to impinge against the projectile deposited in the barrel from the hopper. A pitman 28 is provided for each gun and the pitmen are pivoted at their rear ends to fly wheels 29' secured to the opposite ends of the crank shaft 30 of an internal combustion engine which may be of any well known type and is illustrated in a conventional manner only. Whatever the detail construction of the engine may be, it is secured upon the turn table 6 in rear of the center thereof, and midway between the vertical planes of the guns 22. The pitmen 28 may be disposed at any desired position relative to each other so that the guns will discharge simultaneously or successively at any desired intervals. In Fig. 1 of the drawings, the pitmen are illustrated as arranged to fire at intervals somewhat less than 90 degrees of the engine fly wheel with a relatively long period of rest between the last discharge and the first discharge of a subsequent pair of discharges. If it be desired to have the discharges occur at equal intervals it is only necessary to couple the pitmen to the engine at diametrically opposite points of the engine cranks shaft.

In rear of the hopper 24, a shield 32 is secured and rises therefrom so that the gunner may be shielded from the fire of an enemy, and this shield is equipped with peep holes and shutters 33 to cover the peep holes as will readily be understood.

It is thought that the operation of my improved gun will be readily understood. The automobile or truck is driven to the point of attack in the usual manner and, after reaching the place where the guns are to be discharged, the chauffeur takes a position behind one of the shields 32 and starts the engine 31, after having obtained the proper range so that the projectiles fired from the gun will hit the desired mark. The engine 31 should be of high power so that its crank shaft will rotate very rapidly.

As the pitmen are coupled directly to the crank shaft they will reciprocate very rapidly and the plungers 29 will reciprocate within the gun barrels, at the same rate. The outlet 35 of the hopper is of such dimensions that but one projectile may pass therethrough and, consequently, the projectiles will be admitted singly into the gun barrel and a weak spring 36 is disposed at the mouth of the outlet to retard the escape

of the projectiles so that when the gun is aimed downwardly, the projectiles will not pass into the barrel faster than the plunger works, and, consequently, roll from the barrel without having received the required firing impulse. When the plunger 29 is at the rearward limit of its stroke, the outlet from the hopper will be uncovered and, consequently, a projectile, which may be a bullet or a gas ball or other device, may drop from the hopper into the gun barrel. As the plunger moves forward it will impinge forcibly against the projectile and the impact will eject the projectile from the barrel. The invention is designed more particularly for application to small machine guns of short range which are used in trench fighting and the weight and length of stroke of the plunger may be easily proportioned so that the momentum of the plunger impacting against the projectile will discharge the same from the gun very rapidly and forcibly. As there will be no powder needed to operate the gun nor any gases generated within or admitted to the gun barrel, the gunner will not be hampered by smoke obstructing his vision and betraying his location to an enemy. Guns mounted and operated in accordance with my invention will be obviously of very compact construction and arrangement and may be very easily operated at a minimum expense.

Having thus described the invention, what I claim as new is:

1. The combination of a traveling support, a pedestal thereon, a platform hinged upon the pedestal for movement in a vertical plane, an internal curved rack secured to and depending from the platform, a shaft journaled in the pedestal, a pinion on said shaft, a second pinion meshing with the first-mentioned pinion and with the rack, a gun mounted on the platform, and means on the platform exterior to the gun for firing the same.

2. The combination of a traveling support, a platform mounted upon the support, a turn table fitted upon the platform and having a rack on its edge, a vertical shaft carried by the platform, a pinion on the lower end of said shaft meshing with the rack on the edge of the turn table, a gun mounted on the turn table, and means on the turn table exterior to the gun for firing the same.

3. The combination of a traveling support, a gun mounted thereon and having its rear end open and provided with longitudinally extending notches in its top and bottom at said end, a hopper on the gun, a plunger slidably mounted in the bore of the gun, a motor in rear of the gun, and a pitman connecting the motor with the plunger and playing through the open rear end of the gun and the longitudinal recesses therein.

4. The combination of a traveling support, a platform mounted on the support, means for adjusting the platform in horizontal and vertical planes, guns mounted upon the platform at opposite sides at the center thereof, an engine mounted upon the platform in rear of the center thereof and

between the vertical planes of the guns, said engine having a crank shaft, plungers slidably mounted in the guns, and a pitman connecting the ends of the crank shaft of the engine with the respective plungers. 10

In testimony whereof I affix my signature.
HORACE J. PETERSON.
